MOCCASIN

Fred J. Grams, Mishawaka, Ind.

Application February 19, 1932. Serial No. 594,029

3 Claims. (Cl. 12—142)

This invention appertains to the art of making moccasins, and has for one of its primary objects the provision of novel means for forming the vamp of the moccasin, whereby the vamp can be given a predetermined and rigid form, so as to facilitate the correct shaping of the moccasin and the sewing thereof.

Another important object of my invention is the provision of novel means for uniting the toe-piece of the upper with the vamp, whereby a strong, durable and waterproof connection will be had, and whereby the moccasins can be quickly made with a minimum amount of effort on the part of the operator.

In the uniting of the toe-piece of the upper with the vamps of moccasins, it is customary to sew the upper to the vamp by hand. This has been necessary due to the form of the upper. Considerable difficulty has been experienced with moccasins where the upper is connected with the vamp by hand stitching. The stitches have a tendency to pull, so that the water-tight connection will be lost, and these stitches break incident to the constant bending of the moccasins when the same are in use. Further, where the moccasins are hand made, a single operator can only make between six to twelve pairs a day.

It is, therefore, a further object of my invention to provide means whereby the upper can be united to the vamp by machine stitches, so as to give a strong and water-tight joint and whereby a single operator will be permitted to sew approximately two hundred pairs of moccasins during the working day.

A further object of my invention is the provision of means for uniting the upper and vamp of a moccasin together, in which the upper is so formed as to provide a U-shaped channel around the marginal edge thereof, which gives substantially spaced vertical walls for closely engaging the inner and outer faces of the upper edge of the vamp, whereby a horizontal row of stitching can be made on a machine for passing through the walls of the channel of the upper and the top edge of the vamp. The machine made stitches draw the walls of the channel into tight and intimate contact with the vamp.

A further object of my invention is the provision of novel means for forming a moccasin, in which a substantially U-shaped channel is formed in the upper for receiving the upper edge of the vamp, the upper edge of the vamp being held in the channel by the use of a suitable cement, which will allow the handling of the upper

and vamps as a unit, so that the same can be sewed on a machine.

A still further object of my invention is to provide a moccasin of the above character, having a molded vamp, so that the vamp will be of a predetermined shape and configuration, and whereby the upper can be connected therewith in a novel and efficient manner.

With these and other objects in view, the invention consists in the novel construction, arrangement and formation of parts, as will be hereinafter more specifically described, claimed and illustrated in the accompanying drawing, in which:

Figure 1 is a transverse section through a moccasin constructed in accordance with my invention, illustrating the novel means employed for connecting the toe-piece of the upper with the vamp of the moccasin;

Figure 2 is a detailed perspective view of the toe-piece of the upper and;

Figure 3 is a perspective view of the molded vamp, showing the predetermined shape thereof.

Referring to the drawing in detail, wherein similar reference characters designate corresponding parts throughout the several views, the letter A generally indicates a moccasin constructed in accordance with my invention. As shown, the moccasin A comprises the novel vamp V and the toe-piece T of the upper. The toe-piece and the vamp are united in a novel manner, by machine stitches, as will be later set forth.

In the forming of moccasins, it is customary to fold the leather for the vamp and to unite the toe-piece of the upper to the vamp by hand stitches. This is a tedious operation and not only do the stitches tend to pull apart, but these stitches also break under constant bending of the moccasin, when the same is in use.

Further, where the moccasin is sewed by hand, an operator working at a maximum speed cannot make more than twelve pairs of the moccasins in a single working day. With my improved method of uniting the toe-piece of the upper with the vamp by machine stitching, a single operator can average two hundred or more pairs of moccasins a day.

In the formation of my moccasin, I preferably use a vamp V, which is constructed and formed in a novel manner, which forms an important part of my invention. The vamp formed according to my invention, can be connected to the upper by my improved seam, or can be con-

nected to an upper by the ordinary hand butt seam.

The leather from which the vamp is made, is molded on a hot iron, so that the entire vamp is given the desired and predetermined shape, which conforms to the foot and to the last. This provides a substantially rigid formed vamp having the bottom wall or sole 5 and the outer vamp walls 6. After the vamp has been molded into the predetermined shape, the same can be trimmed of excess leather.

In the forming of the upper, the toe-piece T has the outer edge of the top wall 7 formed with an up-struck marginal channel 8 of a substantially inverted U-shape, forming inner and outer substantially vertically spaced parallel walls 9 and 10. These walls 9 and 10 are placed over the upper edge of the vamp and are temporarily united therewith, by the use of cement or other desired adhesive. By this arrangement, the upper and vamp are temporarily united after which the upper and vamp are sewed together on a machine which forms horizontally disposed lock stitches 11.

As shown, the horizontally disposed lock stitches 11 extend through the parallel walls 9 and 10 of the upper and through the top edge of the side walls of the vamp. I found that the upper and vamp can be effectively sewed with the attachment of a Union lock stitching machine, or with the attachment of the Goodyear outsole stitching machine.

After the upper has been connected with the vamp by my method, excess leather can be trimmed from the toe piece close to the stitching.

From the foregoing description, it can be seen that I have provided a novel moccasin embodying an improved type of vamp and an improved means for connecting the toe-piece of an upper with the vamp.

Changes in details may be made without de-

parting from the spirit or the scope of my invention, but what I claim as new is:

1. The method of making a moccasin, which consists in first forming a U-shaped channel having spaced parallel walls on the marginal edge of the upper, second placing the upper edge of the vamp in the channel; then temporarily uniting the top edge of the vamp with the walls of the channel by an adhesive, and finally machine stitching through the walls of the channel and the top edge of the upper with the machine stitching disposed in a horizontal plane at right angles to the walls of the channel and the side walls of the vamp. 80 85

2. The method of making a moccasin, which consists in first molding an inverted U-shaped channel on the marginal edge of an upper, second molding a vamp into a predetermined substantially rigid shape, third placing the top edge of the vamp in the channel; then uniting the top edge of the vamp with the walls of the channel by an adhesive, and finally machine stitching through the edge of the vamp and walls of the channel with the stitching disposed in a horizontal plane at right angles to the walls of the channel. 90 95

3. The method of making a moccasin, which consists in first molding a vamp into a predetermined substantially rigid shape with upstanding side and connecting front walls, second molding an upper toe piece from a single blank of material to form a body portion and an inverted U-shaped marginal channel; placing the upper edge of the side walls and connecting front wall in said channel; then temporarily uniting the upper edge of the vamp with the walls of the channel, and finally stitching through the walls of the channel and the upper edge of the side walls and connecting front wall of the molded vamp. 100 105 110
